UNITED STATES PATENT OFFICE.

CHARLES PIGUET, OF LYON-VAISE, FRANCE, ASSIGNOR TO LA SOCIÉTÉ PIGUET & CIE., OF LYON-VAISE, FRANCE.

VALVE FOR MOTORS.

SPECIFICATION forming part of Letters Patent No. 689,988, dated December 31, 1901.

Application filed November 30, 1900. Serial No. 38,261. (No model.)

To all whom it may concern:

Be it known that I, CHARLES PIGUET, a citizen of the Republic of France, residing at No. 2 Rue de Paris, Lyon-Vaise, in the department of Rhône and Republic of France, have invented a new and useful Improvement in Valves for Motors, of which the following is a specification.

The invention which forms the object of the present application for Letters Patent is designed to allow of motors working without noise or danger with exhaust-pressures variable within very wide limits. This result is obtained without it being necessary to vary the bore, the overlap, or the stroke of the escape-distributer—that is to say, without altering the degree of compression given by the main stops or the exhaust-valve. Let us take, for example, a condensing-engine the degree of compression of which is suitably regulated, theoretically, in order that the pressure at the end of the stroke may attain a given amount. If the exhaust-pressure be modified so as to bring it up to or even above the atmospheric pressure without altering the amount of compression, a much higher pressure will be obtained toward the end of this period of compression than in the preceding case and even greatly exceeding the admission-pressure if the waste space is small. From this imperfection of the diagram there will result violent shocks to the cross-head of the motor and danger of breaking the mechanism, which is thereby subjected to greater strains than those for which it was constructed. My invention obviates these defects by doing away with their cause. For this purpose during the period of compression a portion of the motive fluid retained in the cylinder after the closing of the large stops or the exhaust-valves is allowed to escape. This prolonged eduction is easily effected by means of an aperture kept open during the period of compression and closed during the periods of admission and expansion. These openings and closings are effected by the main valve alone. It is needless to describe all these means in detail in order to set forth the nature of this invention, and the application of the most simple one will now be described with reference to the accompanying drawings

as obtained by means of a principal distributor in continuous rotation, doing away entirely with the auxiliary distributor.

The escape-outlet discharges into a pipe 55 open to the air or discharging into the escape reservoir or collector, condenser, receiver, or the like. A plug placed along this pipe and operated from the outside of the motor allows the section of the prolonged eduction to increase or diminish, as desired. It will therefore be understood that both during the working or the stoppage of the motor by shifting the plug the quantity of fluid escaping through the outlet can be regulated and the compression be brought to a point which avoids shocks and obviates danger of breakage. It is obvious that the period of this prolonged eduction can be fixed with regard to the results to be attained.

In the accompanying drawings, Figure 1 shows the vertical section on the line A B C of Fig. 2 of the motor-base provided with this invention. Fig. 2 is a plan view of Fig. 1 seen from the interior of the motor.

The escape-disk *a* is pierced by ports *b*, which in rotating open and close the fixed ports *c*, pierced in the base *d* of the motor and opening into the escape-chamber *e*. When the ports *b* of the distributing-disk *a* stop at 80 the same point as the ports *c* of the base *d*, the eduction is terminated and compression begins. The fixed port *f* of the prolonged eduction will, however, still be in connection with the cylinder when the ports *c* of the base 85 are closed, as will be seen from the drawings. The fixed port *f* can therefore prolong the eduction until the stoppage of the distributor-port *b* closes it. At this moment the motor-piston will be near its dead-point and the period of admission about to commence. The section of the fixed port *f* determines the period of the prolonged eduction. This port communicates with a pipe *g*, which discharges into the escape-chamber *e* for the motive 95 fluid, or even directly into the open, if working with free escape. There is a stop-cock in the pipe *g* of any preferred kind—for instance, a conical valve, the point *h* of which can be made to press on its seat *i* or move away therefrom. The cone is operated by means of a screw *j*, accessible from the exterior of the

base. By moving the cone toward or away from its seating the section of the pipe *g* can be varied at will, and consequently also the quantity of the fluid discharged through the 5 prolonged ejection.

What I claim is—

1. In a motor adapted to be operated by a fluid under pressure, a main outlet, a main valve, and a secondary adjustable outlet-channel controlled by the said main valve.
2. In a motor operated by a fluid under pres-

sure, in combination the base *d* the ports *c*, the fixed port *f*, the exit-tube *g*, the valve *h*, and the screw-shaft *j*.

In testimony whereof I have signed my 15 name to this specification in the presence of two subscribing witnesses.

CHARLES PIGUET.
